UNITED STATES PATENT OFFICE.

ORRIN B. BOLTON, OF GRAND RAPIDS, MICHIGAN.

DESIGN FOR A PATCH FOR SAWS.

SPECIFICATION forming part of Design No. 31,716, dated October 24, 1899.

Application filed September 26, 1899. Serial No. 731,682. Term of patent 14 years.

To all whom it may concern:

Be it known that I, ORRIN B. BOLTON, a citizen of the United States, residing at Grand Rapids, in the county of Kent and State of Michigan, have invented and produced a new and original Design for Patches for Saws, of which the following is a specification, reference being had to the accompanying drawings, forming part hereof.

Figure 1 is a perspective view of a patch for saws, showing my design; Fig. 2, an edge view of the same; Fig. 3, an elevation of the semicircular end, and Fig. 4 the same of the rectangular end.

Like letters refer to like parts in all of the figures.

As shown in the drawings, the leading or material feature of my design consists of a thin plate of metal having a rounded end and a beveled edge extending the length of its two sides and across said end.

The surface B of the metal plate or patch

A is a plane surface bounded by parallel sides; an end forming right angles with said sides; and a rounded or semicircular end. The reverse surface C of said patch is provided with a beveled edge D along its two sides and semicircular end, which bevel meets the surface B at its outer edge and extends inward on the surface C, leaving a plane surface C' of smaller dimensions than the surface B, but of substantially the same shape in outline.

Having thus fully described my invention, what I claim as new, and desire to secure by Letters Patent, is—

The design for a patch for saws, substantially as herein shown and described.

In testimony whereof I affix my signature in presence of two witnesses.

ORRIN B. BOLTON.
